UNITED STATES PATENT OFFICE.

DANIEL C. RIPLEY, OF PITTSBURGH, PENNSYLVANIA, ASSIGNOR TO RIPLEY & COMPANY, OF PITTSBURGH, PENNSYLVANIA, A CORPORATION OF PENNSYLVANIA.

DESIGN FOR A JAR.

43,509.

Specification for Design.

Patented Feb. 4, 1913.

Application filed November 27, 1911. Serial No. 662,775. Term of patent 7 years.

To all whom it may concern:

Be it known that I, DANIEL C. RIPLEY, a resident of Pittsburgh, in the county of Allegheny and State of Pennsylvania, have invented a new, original, and ornamental Design for Jars, of which the following is a specification, reference being had to the accompanying drawing, forming part thereof, in which the figure is a side elevation of a jar embodying my design.

I claim:

The ornamental design for a jar, as shown.

In testimony whereof, I have hereunto set my hand.

DANIEL C. RIPLEY.
